UNITED STATES PATENT OFFICE.

EDWARD FERDINAND SCHOLDER, OF HEPLER, KANSAS.

HAY-STACKER.

SPECIFICATION forming part of Letters Patent No. 361,722, dated April 26, 1887.

Application filed September 7, 1886. Serial No. 212,916. (No model.)

To all whom it may concern:

Be it known that I, EDWARD FERDINAND SCHOLDER, a citizen of the United States, residing at Hepler, in the county of Crawford 5 and State of Kansas, have invented a new and useful Improvement in Hay-Stackers, of which the following is a specification.

My invention relates to improvements in hay-stackers; and it consists in certain novel 10 features, hereinafter first fully described, and then specifically pointed out in the claim.

In the drawings hereto annexed, Figure 1 is a perspective view of a hay-stacker embodying my invention, showing it adapted for 15 use. Fig. 2 is a like view of the stacker, showing it folded for transportation; and Fig. 3 is an enlarged perspective view of the foot or runner.

Referring to the drawings, in which like letters of reference denote corresponding parts in all the figures, A designates the supporting-frame of my improved hay-stacker; C, the vertical swinging standard, which is jointed to the supporting-frame in such manner that 25 it can be very freely moved or swung from one side to the other; E, the adjustable arm carried by the swinging standard and inclined upwardly therefrom, so that it will discharge the hay or straw onto the center of the stack, 30 and F the foot or runner in which the lower end of the swinging standard is journaled or stepped, the peculiar construction of the several parts above mentioned being hereinafter fully described.

35 The supporting-frame A comprises two diagonal standards, A', which meet at their upper ends and are there rigidly secured together by any preferred means, and a transverse bar, A'', connecting the said standards at an intermediate point of their length, to strengthen 40 and brace the standards and add to the stability of the structure. The lower extremities of the diagonal standards are rounded or beveled at a, to adapt the standards to slide freely over 45 the surface of the ground in moving or transporting the supporting-frame from one place to another, and to the said lower ends of the standards are secured swivels or loops a', which are pivotally connected thereto by trans- 50 verse pins a'', so that the swivels can be adjusted at an angle and out of line with the standards to permit the stakes B to be driven

therethrough, in order to secure the lower ends of the standards of the supporting-frame against movement or accidental displacement 55 when the stacker is adjusted for use, as clearly shown in Fig. 1 of the drawings.

A strap, B', is affixed to the apex of the supporting-frame A, formed by the upper meeting ends of the diagonal standards A', and this strap is formed into or provided with an eye or loop, b', with which engages a similar eye or loop, c, on a bracket-plate, c', that is rigidly affixed to one of the sides of the oscillating standard C, and at the upper extremity 60 thereof, so that the upper end of the said vertical standard is swiveled to the apex of the supporting-frame, to adapt it to swing in either direction.

To the lower end of the oscillating standard 70 C is secured a plate, d, that is provided with an integral pin or trunnion, d', which projects beyond the lower extremity of the standard, and this pin or trunnion d' is fitted or journaled in a socket, f, formed in the foot or runner F, the said foot or runner being arranged beneath the lower end of the standard, so that the latter will rest or bear thereon and be free 75 to turn or rotate in the socket f in the said runner.

The inclined arm E is normally held at an angle to the upper end of the vertical standard C, and the lower end of the said inclined arm is jointed to the upper end of the standard at e, to adapt the arm to be adjusted at 85 varying angles to the standard and thus adjust the apparatus to stacks of different heights. The said inclined arm is braced and held in its proper adjusted position by means of diagonal rods or bars E', which are pivotally connected at their upper ends to the arm at e', and pivotally and adjustably connected at their lower ends to the oscillating standard C by means of a removable pivot pin or bolt, G, passing through openings g in the lower 90 ends of the arms, and one of a series of openings or apertures, g', in the vertical standard. It will be seen that the lower ends of the braces can be adjustably connected to the vertical standard by removing the pivot pin or bolt G from one aperture g' to the other aperture of the series, and the inclined arm is held 95 very securely and steadily in place by the said braces, as is obvious.

The foot or runner F consists of the parallel side bars, f', which are beveled or inclined at their ends and on their under sides, to permit the bars to run or slide freely over the surface 5 of the ground when transporting or moving the apparatus from one place or stack to another, and these side bars, f', are connected and braced by a transverse plate or bar, f'', which is secured to the side bars, f', in any 10 suitable manner, and to which the bearing f is secured, or in which the said bearing is formed. This foot or runner is held immovably in place when the apparatus is adjusted for use by means of stakes F', which are driven 15 into the ground between the parallel side bars, f', and on opposite sides of the transverse connecting plate or bar f'', as shown in Fig. 1.

H designates a clamp which embraces the lower end of the oscillating standard, and to 20 the free ends of the clamp is secured a bracket, h, which carries a pulley-block, I, which is swiveled or loosely connected to the bracket.

J designates a pulley-block, which is swiveled to the outer end of the inclined arm E of 25 the standard, and K is another block, which is swiveled to the inner end of the said inclined arm and in close proximity to the vertical swinging standard.

L designates an elevating cord or rope which 30 passes through the pulley-blocks J K at the outer and inner ends of the inclined arm, thence down along one of the sides of the vertical standard C and through the pulley-block I at the lower end of the standard. To the end 35 of the elevating rope L which passes through the pulley-block I is connected or secured a whiffletree, l, to which the draft-animal is hitched, as is usual, and to the end of the said rope which passes through the block J is connected 40 an elevating hay fork, m, of any approved or preferred pattern.

M designates straining cords or ropes, which 45 are connected to the lower ends of the diagonal standards A' of the supporting-frame, and to the transverse connecting bar A'' of the said frame.

The oscillating standard C of the stacker is provided with a hook, n, to which the hay-fork is connected, or from which it is suspended when the apparatus is being transported or moved from one place to another.

The operation of my invention will be readily understood from the foregoing description, taken in connection with the drawings.

55 When the apparatus is adjusted for use, as shown in Fig. 1 of the drawings, the oscillating standard C is stepped at its lower end in the shoe or runner F, and thereby supported at its lower end in place, and the supporting-frame A is inclined with relation to the said standard and connected therewith at its upper end, the said vertical standard being thus free to swing in either direction, and being supported very securely in its proper position.

60 The inclined supporting-frame A is held in

its proper place against accidental displacement by means of the stakes B, and the shoe or runner F is likewise held in place by the stakes F', as is obvious. The inclined arm E is adjusted at the proper angle to the vertical standard, and the elevating-rope L passes freely through the pulley-blocks in order to raise and lower the hay-fork m at one end of the said rope L. The vertical standard C can be easily and freely swung around after the 75 fork m has been elevated, to properly discharge the hay or the contents thereof onto the stack, and the angle of the inclined arm can be varied according to the height of the stack.

80 When it is desired to move or transport the stacker from one place or stack to another, the pivot-bolt G is detached and the braces and inclined arm are lowered, as shown in Fig. 2 of the drawings. The stakes B and F' 85 are drawn from engagement with the clevises of the frame A and the runner or shoe F, the fork m suspended from the hook n of the standard C, the straining-cords M connected with the lower ends of the standards A' and 90 the runner F, as shown in Fig. 2, in order to brace the standards and prevent them from becoming displaced, and the whiffletree connected to the runner, whereby the apparatus can be very easily and conveniently drawn 95 over the ground.

From the foregoing description, taken in connection with the drawings, it will be seen that I provide an improved stacker for straw, hay, and grain which is very simple, strong, 100 and durable in construction, and light and portable.

The device can be very easily and readily unfolded and adjusted for use in a short time and as rapidly folded for transportation, and 105 it occupies but very little space, and can be set or adjusted against the wind, so that the latter will not affect it while in operation.

By means of the swinging standard and the inclined adjustable arm E at the upper end 110 of the same the hay can be discharged exactly in the middle of the stack at all times, which is very important in stacking the hay.

Having thus fully described my invention, what I claim as new, and desire to secure by 115 Letters Patent, is—

A hay-stacker comprising a base, a standard stepped in said base, a supporting-frame flexibly connected to the standard at its upper end, and straining cords or wires carried 120 by said supporting-frame and adapted to engage the base when the device is being transported, substantially as specified.

In testimony that I claim the foregoing as my own I have hereto affixed my signature in 125 presence of two witnesses.

EDWARD FERDINAND SCHOLDER.
